UNITED STATES PATENT OFFICE.

WALLACE W. GREENWOOD, OF WORCESTER, MASSACHUSETTS, ASSIGNOR TO NORTON COMPANY, OF WORCESTER, MASSACHUSETTS, A CORPORATION OF MASSACHUSETTS.

SEGMENTAL ABRASIVE WHEEL.

Application filed March 28, 1921. Serial No. 456,094.

To all whom it may concern:

Be it known that I, WALLACE W. GREENWOOD, a citizen of the United States of America, residing at Worcester, in the county of Worcester and State of Massachusetts, have invented certain new and useful Improvements in Segmental Abrasive Wheels, of which the following is a full, clear, and exact specification.

10 My invention relates to a grinding wheel and more particularly to one which is made up of abrasive segments.

In the grinding or shredding of fibrous materials such as wood for the manufacture of paper pulp, it has been common practice to employ a large, solid, sandstone wheel, which is expensive and when only partly worn out must be thrown away. They are, moreover, exceedingly heavy and do not permit of any flexibility in their use because when they are worn out or become cracked or must be discarded for any other reason, the only thing that can be done is to provide another wheel, as the old ones cannot be made 20 to serve any useful purpose in this connection.

An effort has therefore been made to determine whether artificial abrasive wheels may not be used in this work and it has been found that if such wheels are chosen with the proper degree of hardness and size of abrasive particles, they can be used to good advantage. Since such abrasives may be controlled within relatively narrow limits 35 with respect to these properties, the conditions for obtaining a short or long fiber in the pulp or one which is frayed, as is usually preferred, may be ascertained and duplicated for the various kinds of raw material 40 being considered.

On account of the raw materials usually being in large pieces, such as logs in the preparation of wood pulp, a wheel is required which has a much larger diameter and 45 greater width of the peripheral surface or "face" than for grinding metal. It would be exceedingly difficult to make a solid wheel of artificial abrasive which would be suitable for this purpose and the amount of material 50 required would make it very expensive. Consequently, a segmental wheel is necessary and if worn or broken segments may be readily replaced in practice, it is much to be preferred. Such wheels have been built up of 55 sections which fit together and form a hol-

low cylinder, the outer or peripheral surface of which is employed in the grinding action, but previous constructions do not provide nor permit of forming a wheel of sufficient width, in which this can be done. The thickness of the segments also has been limited so that sufficient wear is not obtainable before they must be replaced. Grooves or joints between the segments which run parallel to the axis of rotation are apt to chip or splinter the material being ground, and joints which run parallel to the plane of rotation do not grind the material evenly at these points and also produce splinters, and in both cases an unsatisfactory pulp results. Moreover, wheels 60 of the segmental type have involved various inconvenient methods of clamping the segments to the wheel center or cementing them to it in one way or another, such as upon iron plates, which were in turn fastened to it. 65

It is, therefore, an object of my invention to provide a grinding wheel in which the various difficulties mentioned above will be overcome and in which artificial abrasive segments may be clamped directly to the 70 wheel center in a sufficient number of annular rows to give any width of face or diameter that may be desired and in which the segments may be replaced individually 75 without serious delay.

It is also an object of my invention to provide for the use of segments having such shape as to make the joints between them form an oblique angle to their line of contact with the work. Other objects will be 80 apparent from the following specification.

One form of the type of grinding wheel in which my invention has been embodied is shown by the accompanying drawings, in 85 which:

Figure 1 is a cross section of the wheel taken at right angles to the axis of rotation;

Fig. 2 is a cross section of the wheel through the axis of rotation and along the 100 line 2—2 of Fig. 1;

Fig. 3 is a side view of the assembled wheel; and

Fig. 4 shows a modification of the wheel, in which the joints between adjacent segments are oblique to the plane of rotation. 105

In accordance with my invention, I make a grinding wheel having abrasive segments which form a cylindrical grinding surface, a suitable wheel center and adjustable fas- 110

tening means by which the segments may be securely held in position and attached to the wheel center. These segments 10 consist entirely of bonded abrasive grains and are so shaped as to be held directly by cooperating clamps or other suitable fastening means. For this purpose I may use a wheel center comprising a cylinder or drum 11 and a clamping device which will removably engage the inner portion of each of the abrasive segments and hold it securely to the drum, and in its proper position. A convenient form of clamp, as shown in the drawings, consists of a wedge-shaped strip 12 which fits against a dovetail projection 13 of the segments 10 and bolts 14 passing through perforations in the drum and threaded into the wedge-shaped strip. By tightening the bolts the wedge draws the segments against which it is placed more firmly against the drum and closer together. In the same manner one or more complete annular rows of segments may be built up and held in place upon the drum. The joints 16 and 17 between the segments may be staggered or not as desired. The joints 16 are shown in Fig. 3 as parallel with the axis of rotation and the joints 17 arranged in a zigzag fashion, while in Fig. 4 I have shown all the joints as disposed oblique to a line on the peripheral surface parallel with the axis. The joints between the segments are filled with a suitable cementing material, which should preferably be insoluble, so that the face of the wheel shall be and remain continuous in its action upon the work.

This type of wheel is mounted upon a suitable wheel spindle such as 20 by means of flanges 21 and 22 which serve to hold the rows of segments together and to support the drum concentrically during the grinding operation. In case the flanges are threaded upon the spindle as shown in the drawings, the threads for the flanges 21 and 22 should be right and left-handed respectively and so mounted that the resistance of the grinding action shall tend to force them onto the spindle.

In constructing a wheel according to the adaptation of my invention which is shown in the drawings, a flange 21 is threaded upon the spindle 20 after having a ring 23 fastened on its inner side by bolts 24. The drum 11 is then set over the ring 23 and fastened to the flange 21 by dowel pins 25. Two of the wedge shaped strips 12 are then set upon the drum and loosely engaged by bolts 14 through suitably spaced holes in the drum. The dovetailed portion 13 of one of the abrasive segments 10 is then slipped between the wedge shaped strips 12 until it butts up against the flange 21 and the bolts 14 are then tightened, drawing the wedge shaped strips downward upon the

drum and securing the segment 10 between it and the next similar strip on the opposite side of the dovetail. The wedges will not all be fully tightened until sufficient segments have been set around the drum in 70 similar fashion to form a complete cylindrical surface and similarly clamped by other wedge shaped strips, but after this has been done they may be gradually tightened until all of the segments are securely held 75 against the drum and in their relative positions. Another annular row of similar segments, of such shape as to fit the inner edges of those already in position, may be set upon the drum in contact with the first row thus 80 formed, and in a similar manner other rows may be put in position until the desired width of the wheel is formed, which should preferably correspond with the width of the drum. A second flange 22, to which the 85 ring 26 has been fastened by means of bolts 27, is then threaded upon the wheel spindle 20 until the outer edge of the flange comes into contact with the edge of the drum and of the abrasive segments, and tightened to 90 hold them in position as shown.

If desired, the segments used may be ground so as to make a close and exact fit, one to the other, but this involves a considerable amount of care and time. It is 95 therefore preferable in ordinary practice, and equally satisfactory, to leave a narrow space 16 between the segments and also a narrow space 17 between the annular rows 100 of segments. Then, while the wheel is being 100 constructed a cement may be applied to the sides of each segment which will come into contact with the others as they are put into position. Or, after the segments have been assembled, a thin fluid cement mixture may 105 be poured into the fissures between them, care being taken that none is permitted to flow upon the grinding surface.

The wheel thus assembled is ready for the shredding of such material as wood in the preparation of wood pulp or similar substances. Obviously the wheels may be used until the segments have been worn down practically to the wedge shaped strips, when it will become necessary to replace them. 110 This may be done readily, and moreover with this type of construction, in case an additional segment is broken, as may occur when rough work is being handled, it may be promptly replaced by removing one of the flanges, loosening the wedges at each side of the broken segment, slipping it out from between them and inserting a new segment in its place, tightening the bolts and replacing the flanges, when the wheel is 115 120 125 again ready for use.

In my method of construction, various shapes of segments may be used, but those are preferred forming joints which will come into contact with the work at an angle to the 120

line of contact. The difficulties of splintering or grinding the work unevenly, which have been hitherto experienced, are thus avoided. Two shapes of segments are shown in the drawings, in which these conditions are provided for. It is also to be noted that the segments in each of the wheels illustrated in Figs. 3 and 4 are of similar size and shape, thus making them interchangeable and simple and economical to manufacture.

It will be apparent from this disclosure of the invention that various modifications can be made therein, without departing from its scope, and that it may be adapted to other grinding operations and conditions than those mentioned. Such modifications and adaptations, however, are to be considered as comprehended and included by this specification or the appended claims.

Having thus described my invention, what I claim as new and desire to secure by Letters Patent is:

1. A grinding wheel comprising a cylindrical drum adapted to be mounted concentrically on the wheel spindle, abrasive segments mounted thereon and forming a cylindrical grinding surface, each of said segments having a projecting lug on an inner portion, and clamping means including a removable wedge to engage said lug with adjustable pressure and replaceably fasten the segment to said drum.

2. In combination with a wheel spindle, a grinding wheel comprising a cylindrical drum having perforations therethrough, separable wheel flanges fastened to the ends of the drum for mounting the same concentrically on the wheel spindle, abrasive segments having inner cylindrical surfaces fitting the drum and forming an outer cylindrical grinding surface, and clamps passing through the perforations in said drum and

removably engaging said segments and clamping them in position.

3. In combination with a wheel spindle, a drum, a plurality of abrasive segments having inner surfaces fitting the drum and forming a cylindrical abrading surface, means to clamp the segments removably and adjustably on the drum and flanges supporting the drum which are removably mounted on the spindle and engage the end segments.

4. In combination with a spindle, a grinding wheel thereon comprising a cylindrical drum, a plurality of similar abrasive segments forming a cylindrical grinding surface, each of said segments being provided with a dovetailed projection on its inner portion; wedge shaped clamps removably engaging said dovetailed projections and adjustably fastening said abrasive segments to said drum, and flanges supporting the drum which are removably mounted on the spindle and clamp against the end segments.

5. A grinding wheel comprising a plurality of annular rows of abrasive segments forming a cylindrical grinding surface, the joints between the rows of segments being staggered and each joint line forming an angle with a plane perpendicular to the axis of rotation, a wheel center, and means for removably mounting said segments upon said wheel center.

6. A grinding wheel comprising a plurality of annular rows of abrasive segments forming a cylindrical grinding surface, each joint between the segments being oblique with respect to any line on the peripheral surface of the wheel which is parallel to the axis of rotation.

Signed at Worcester, Massachusetts, this 25th day of March, 1921.

WALLACE W. GREENWOOD.
